United States Patent Office

Des. 200,427
Patented Feb. 23, 1965

200,427

FRYING PAN LID

Ruth F. Merrick, San Diego, Calif.
(3857 Hazelwood Ave., Las Vegas, Nev.)

Filed July 31, 1964, Ser. No. 81,100

Term of patent 14 years

(Cl. D44—1)

Fig. 1

Fig. 3

Fig. 2

FIG. 1 is a top perspective view of a fry pan lid showing my new design.

FIG. 2 is a top plan view thereof; and

FIG. 3 is a sectional view on line 3—3 of FIG. 2.

I claim:

The ornamental design for a fry pan lid, as shown.
